UNITED STATES PATENT OFFICE.

ERNEST H. BENNETT, OF EAST ORANGE, NEW JERSEY, ASSIGNOR TO JOHN H. BROMLEY AND EDWARD BROMLEY, OF PHILADELPHIA, PENNSYLVANIA.

DESIGN FOR A RUG.

SPECIFICATION forming part of Design No. 28,834, dated June 7, 1898.

Application filed April 30, 1898. Serial No. 679,405. Term of patent 3½ years.

To all whom it may concern:

Be it known that I, ERNEST H. BENNETT, a citizen of the United States, residing at East Orange, Essex county, New Jersey, have invented and produced a certain new and original Design for a Rug, of which the following is a full, clear, and exact description, reference being had to the accompanying drawing, forming a part of this specification.

10 My invention relates to the surface ornamentation of woven fabrics, such as Smyrna and other woven rugs. Its distinguishing features consist of an outer rectangular line-border a and a like-shaped field center b, 15 between these a chain-like series of figures c, and within the field center a series of small floral figures within an irregular line figure d, the actual center being occupied by a figure f.

I claim as new—

The design for a rug, substantially as set forth.

In testimony whereof I have hereunto affixed my signature this 25th day of March, A. D. 1898.

ERNEST H. BENNETT.
